STRAP WATCH

Filed Nov. 16, 1929

Arthur E. Manheimer.

Charles St. Niles 1711

UNITED STATES PATENT OFFICE

**ARTHUR E. MANHEIMER, OF CHICAGO, ILLINOIS, ASSIGNOR, BY MESNE ASSIGNMENTS,
TO LUG-LESS WATCH COMPANY, OF CHICAGO, ILLINOIS, A CORPORATION OF
ILLINOIS**

STRAP WATCH

Application filed November 16, 1929. Serial No. 407,648.

This invention relates to improvements in strap watches and the like, of the type commonly secured to the wrist, ankle or any other appropriate portion of the body of a 5 wearer, by means of a bracelet, strap, sautoir, or the equivalent. The invention relates more particularly to improved means for attaching a bracelet, strap, or other securing device to the case of a watch of this character, the securing device being made of 10 metal, leather, or any desirable material.

As will be apparent hereinafter, the subject matter presented herein is related to the inventions disclosed in my co-pending applications, namely, Serial No. 279,386, entitled 15 "Wrist watch", filed May 21, 1928, and Serial No. 280,786, entitled "Strap watch", filed May 26, 1928; but the present invention incorporates refinement in structure not present 20 ent in the aforesaid co-pending cases.

As stated in my aforesaid co-pending cases, means for attaching a strap or the like to a watch heretofore known have, in most instances, proven objectionable in that the 25 means projected from the case of the watch in an unsightly manner, and in such a way that they frequently became entangled with the apparel of a wearer and maintained the bracelet end in such a position of exposure 30 that they were frequently prematurely and noticeably worn. Moreover, these formerly known securing means were quite often difficult to properly connect, and in most cases necessitated the attention of a skilled repair 35 man or jeweler.

Accordingly, it is an object of this invention to provide means for connecting a strap or the like to a watch in such a manner that the resulting appearance is that of the strap 40 passing entirely through the watch, the connecting or securing means being entirely invisible.

Another object of this invention is to provide means for connecting a strap or the 45 equivalent to a watch in a simple and expeditious manner consisting of simply laying the strap end in position and snapping on a cover of the watch.

Still another object of this invention is the 50 provision of means for attaching a strap or

the like to a watch, which means, although they necessitate some modification in the structure of the case body, yet require no enlargement of the case body and are disposed entirely within the watch case.

While some of the more salient features, characteristics, and advantages of the means embodying the present invention have been above pointed out, others will become apparent 55 from the following disclosures.

The invention includes these and other features of construction and combinations of parts hereinafter described, and shown in a preferred form in the drawing, as more particularly indicated by the claims.

On the drawing:
Figure 1 is a plan view of a watch with a strap or bracelet attached thereto by means embodying the present invention, this figure showing the resultant appearance after the 70 strap has been attached.

Figure 2 is an enlarged fragmentary plan view of the central portion of the structure shown in Figure 1, with the bezel or front cover of the watch removed.

Figure 3 is a fragmentary vertical sectional view taken substantially as indicated by the line III—III of Figure 2.

Figure 4 is a vertical sectional view taken substantially as indicated by the line IV—IV 80 of Figure 3.

Figure 5 is a view similar to Figure 3, disclosing a slightly different form of the present invention.

Figure 6 is a fragmentary vertical sectional view taken substantially as indicated by the line VI—VI of Figure 5.

As shown on the drawing:
In the structure selected for illustrating an embodiment of the present invention, 90 there is shown a watch 10, which, in this instance, is of substantially the type of the commonly known wrist or strap watch. As seen in Figures 1 to 4 inclusive, a strap or bracelet 11, in two pieces, is attached to the 95 watch 10, the strap being shown as made of leather, but it is to be distinctly understood that the strap may be cloth, metal, or any other desired material. The watch 10 comprises the customary case body 12 having a 100

relatively large central aperture 13 therein for the reception of the watch movement, a back cover 14, and a bezel or front cover 15, the latter bearing the watch crystal 16 in any well known manner. The back cover 14 has an inwardly turned rim 17 thereon which snaps over a shoulder 18 formed on the rear side of the case body, and the front cover or bezel 15 is secured to the case body by a similar snapping engagement with a shoulder 19.

Since each portion of the strap 11 is attached to a side of the case body in identical manner, it will only be necessary herein to describe the means for and method of attaching one portion of the strap to the case. It will be noted that the strap 11, as is customary in devices of this character, is provided with an enlarged portion or loop 20 adjacent the inner end thereof, and a pin 21 is preferably passed through this loop to maintain the same in expanded position. As is seen more clearly in Figures 2, 3, and 4, the case body 12 is provided with a recess 22 adjacent an end thereof, the recess being sufficiently large to accommodate both the loop 20 and the pin 21. From the disclosure in Figure 3, it will be noted that the recess is curved in the bottom thereof in the same manner as is the loop 20, so that the loop will be substantially embraced by the recess and an upwardly extending portion or lip 23 will abut the strap adjacent the terminus of the loop. The pin 21 which passes through the loop 20 bears at each end thereof a small projection or tip 24 which rests in a narrowed extension 25 of the recess 22 and serves to hold the strap end in position until the watch cover, in this instance the bezel 15, is snapped into place.

With reference now to Figures 3 and 4, it will be seen that the bezel 15 in this instance has an inwardly turned margin 26 thereon which overlies the recess 22, the margin adjacent the outer edge thereof being provided with a downwardly turned lip 27 which embraces and hugs the loop in the strap end in the same manner as the lip 23 upon the case body does upon the opposite side of the strap. It will be noted also that the margin 26 upon the bezel extends inwardly sufficiently for snapping engagement with the end portion of the shoulder 19 on the case body, this end portion of the shoulder being set in somewhat farther than would be the case if the recess 22 were not present. It will be apparent, therefore, that the bezel 15 will have intimate contact with the case body entirely therearound, and that due to the margin 26 and lip 27, the strap end or loop 20 will be held firmly in position, i. e., firmly connected to the case body, and dust effectively prevented from entering through the recess 22 and eventually into the space between the case body and cover.

In operation, the structure just previously described herein is extremely simple and effective. Assuming now that the strap is separate from the watch and it is desired to attach the two, it is simply necessary to remove the bezel 15 from the watch, insert the pin 21 in the loop 20 of the strap, and then merely lay both pin and strap into the recess 22. The tips 24 upon the pin will automatically fall within the extension 25 of the recess and this latter engagement will hold the strap in position in the recess 22 until the bezel has been replaced upon the watch case body. The mere replacement of the bezel secures the elements in their proper position and firmly holds the strap connected to the watch. Of course, as pointed out hereinabove, both sides of the watch case are constructed in identical manner, and the two strap ends are attached preferably in a single operation. It should also be borne in mind that if, for any reason, it is desired to reverse the mechanism, that the back cover 14 of the watch may be equally as well utilized to hold the strap in position.

As seen in Figures 1 to 4 inclusive, the strap is made of leather, and when the strap is made of leather, cloth, or some similar substance, the pin 21 maintains the loop 20 in expanded position, so that there is no possibility of the loop pulling out between the lips 23 and 27. However, when a metal strap is utilized, these straps commonly having an integral metal loop on the end thereof or other suitable formation, the pin 21 is not in fact necessary, since the metal loop will always retain its normal shape. With the metal loop, the only function the pin would serve would be to retain the loop in position by engagement of the tips 24 in the extensions 25 of the recess until the operator had opportunity to replace the cover.

In Figures 5 and 6 I have shown a slightly modified form of the present invention. In this instance, a watch is shown comprising a case body 28, a back cover 29 which may be snapped onto the case body in the manner previously described, and a front cover or bezel 30 carrying the customary crystal 31 therein.

The bezel 30 has the ordinary inwardly turned rim completely therearound which snaps over a shoulder 32 formed on the case body. However, the case body is provided at each side thereof with a removable portion 33 which slopes downwardly as at 34 and laterally as at 35 and seats within a similarly shaped recess in the case body, whereby the removable piece 33 is effectively dovetailed in the case body against a lateral pull. As indicated at 36, the removable piece 33 is also shouldered adjacent the top thereof to permit the bezel 30 to snap thereover so that the bezel is in intimate engagement with the case body at all points therearound.

The removable piece 33 is also provided with a suitable key-hole slot therein which receives a loop 37 upon the end of a metallic strap 38.

- 5 In the operation of the structure disclosed in Figures 5 and 6, to attach the strap to the watch, it is simply necessary to remove the bezel 30, insert the loop 37 of the strap by relative endwise motion into the removable piece 33, lay the removable piece 33 in its respective socket in the case body, and snap the bezel back into position. It will also be apparent that due to the shoulder 36 upon the removable piece no dust may enter the 10 interior of the watch case. If it is desired to use a strap made of soft material, such as leather, cloth, or the like, with the structure shown in Figures 5 and 6, any suitable form of pin may be inserted in the loop 15 in the strap end to maintain this loop in expanded position and prevent the same from pulling through the narrowed opening of the keyhole slot.

As in the case of the previously described 20 form of the invention, this form may also be incorporated or utilized with either of the watch covers.

From the foregoing, it will be apparent 25 that I have provided effective and simple means for attaching a bracelet, strap, sautoir, or the like to a watch case, the means of attachment being entirely concealed by a cover of the watch case. Moreover, dust is effectively excluded by the cooperation 30 between the cover and case body, which cooperation serves to effectively hold the strap connected to the case. Furthermore, the construction set forth herein is extremely 35 simple both to manufacture and use, is very durable, and also economical.

It will also be evident from the foregoing 40 that the present invention embodies a new method of attaching a bracelet, a strap, or the like for a watch case, which method is deemed apparent from the previous descriptions herein.

I am aware that numerous details of construction may be varied through a wide range 45 without departing from the principles of this invention, and I, therefore, do not purpose limiting the patent granted, otherwise than necessitated by the prior art.

I claim as my invention:

1. A watch case including a case body and 50 a cover therefor, said body having a recess in the margin thereof beneath said cover, a strap having a shouldered end portion disposed in said recess, and means associated with said body and cover and engaging the shoulders of said portion to prevent dust 55 entering between said recess and cover.

2. In a connection of the class described, a 60 watch case including a body part and a cover part, means for attaching the case to a wearer, said parts together providing a constricted

recess, and said means having a portion fitting in said recess, said parts preventing removal of said portion from said recess.

3. In a connection of the class described, a 65 watch case including a case member, an attaching member therefor, one of said members having a recess and the other having a portion fitting in said recess, and means on one of said members for constricting said recess to prevent separation of said members by movement of the other member through the constriction of the recess, said means being readily removable to allow separation of said members.

4. A watch case including a case body and 70 a cover therefor, said body having a recess beneath said cover, and means for attaching said case to a wearer, said means having an end portion provided with a shoulder and layable in said recess when said cover is removed, said cover, when replaced, engaging said shoulder and thereby retaining said portion in said recess.

5. As an article of manufacture, a watch 75 case including a case body, a cover for said body connectible with and having a portion in spaced relation to the body, said body having a recess beneath said cover and communicating with the space between said body and cover for the reception of a strap end, and means associated with said case in such a manner that said cover will snap on said body at all points therearound.

6. A watch case including a cover and a 80 body having a slot extending along one margin thereof, a fastener for said case and having means substantially coextensive with and disposed in said slot, and means embracing the first means and engaged by said cover for connecting said fastener to said body.

7. A watch case including a cover and a body having a slot extending along one margin thereof, a fastener for said case and having means substantially co-extensive with and disposed in said slot, and means embracing the first means and engaged by said cover for connecting said fastener to said body, the second means being also substantially co-extensive with said slot.

8. In a device of the class described, a watch 115 case having a recess extending along a margin thereof, a strap for securing the case to a wearer, said strap being enlarged at one end, a removable piece substantially co-extensive with and fitting in said recess and constituting substantially a continuation of the adjacent marginal portions of the case, said piece having a constricted recess in which said enlarged end is carried.

9. In a device of the class described, a 120 watch case having a recess extending along a margin thereof, a strap for securing the case to a wearer, said strap being enlarged at one end, a removable piece substantially co-extensive with and fitting in said recess and

constituting substantially a continuation of the adjacent marginal portions of the case, said piece having a constricted recess in which said enlarged end is carried, said case including a body and a cover, said body and piece providing together a continuous rabbit in which said cover is snugly and removably received, whereby said piece is retained in the first mentioned recess.

10. In a device of the class described, a watch case comprising a body and a cover together providing along a margin thereof a constricted recess, a removable piece substantially filling said recess and forming a substantial continuation of the adjacent marginal portions of said body and cover, and a fastener removably connected to said piece.
11. In a connection of the class described, a watch case comprising a body provided with a recess extending along a margin thereof, said recess being closed at its ends and open along two sides, a cover cooperating with said body and closing one of the open sides of the recess and partially closing the other open side thereof, and a fastener for said body, said fastener having an enlarged end substantially filling said recess, whereby the fastener is connected to the body.

In testimony whereof I have hereunto subscribed my name at Chicago, Cook County, Illinois.

ARTHUR E. MANHEIMER.
